UNITED STATES PATENT OFFICE.

LILLIAN F. DOTY, OF CHICAGO, ILLINOIS.

UNION-UNDERGARMENT.

1,255,718.

Specification of Letters Patent.

Patented Feb. 5, 1918.

Application filed September 22, 1916. Serial No. 121,656.

To all whom it may concern:

Be it known that I, LILLIAN F. DOTY, a citizen of the United States, residing at the city of Chicago, in the county of Cook and State of Illinois, have invented certain new and useful Improvements in Union-Undergarments, and do hereby declare the following to be a full, clear, and exact description of the invention, such as will enable others skilled in the art to which it appertains to make and use the same.

This invention relates to apparel, and more especially to bifurcated garments; and the object of the same is to provide such a garment as a union suit with a seat piece so constructed that it will stay normally closed at the crotch and that it will provide for extra fullness at certain points.

This object is carried out by the means hereinafter more fully described and claimed, reference being had to the drawings wherein:—

Figure 1 is a front elevation and Fig. 2 a rear elevation of a garment embodying this invention as the same would look when hung up.

Fig. 3 is an enlarged rear elevation of the lower portion of such garment with the legs spread slightly to more clearly illustrate the details of the invention.

Fig. 4 is a plan view of the seat piece in its entirety and before it is applied, and Fig. 5 is a perspective view of said seat piece Shirred at its upper end to produce the desired fullness, and with one of its parts bent upward to the position it will assume when stitched into the garment.

In the drawings, and more especially in Figs. 2 and 3, B designates the body portion down to the waist line at about W of a union garment, and R is the right and L the left leg. This garment may be made in any suitable way and of any suitable material, but we are concerned only with the inside leg seams S; and while I have shown the garment as having a body portion B above the waist line, that portion does not enter into the present invention excepting that with full length body garments or union suits it is desirable to insert a seat piece which will give freedom to wearers of various sizes, will not chafe, and will hang normally closed without the necessity for buttons or other fastening devices. Also it is desirable that seams shall be elimi-

nated as far as possible, to give greater ease to the wearer when sitting.

The seat piece of my garment is by preference cut from a single piece of material in the blank form best seen in Fig. 4, and might be said to consist of a right hand portion or part 1, a complementary left hand portion or part 2, and an upper portion or part 3 extending across and integrally uniting the upper ends of the two side or leg parts which latter therefore might be called bifurcations separated originally by a long upright opening 4. Starting from the point 5 at the extreme top and center of the upper part 3, the upper edge of this part is substantially straight along a line out to the point 6, then curved from 6 rather abruptly to about the point 7, and then curved rather gently down past the upper part 3 and the upper portion of 75 the bifurcation or part 1 to the point 8. Here the line of the outer edge makes a reverse curve outward to the angle 9, thence the edge is carried inward and down to about the point 10 and thence almost straight 80 downward to 11. Beneath the latter point the lower extremity of the part 1 is cut preferably pointed as seen at 12, and beyond the point the inside line 13 rises almost straight alongside the opening 4 to the point 85. 14. From the latter point the other or complementary part 2 of the blank is cut in the same manner except that it is reversed as will be seen, and I do not consider it necessary to duplicate the description. This 90 leaves the entire side piece or part 1 with a substantially triangular extension 15 at its outer edge beyond the dotted line 16, and a long narrow tongue 17 at its lower end beneath the transverse dotted line 18. 95 Across the blank I have dotted a construction line 19 connecting the points 9 for reference below.

In applying this seat piece to the garment shown, the latter is cut across the back 100 on a transverse line 20 at or just below the waistline W, and the inside leg seams S are opened for a considerable distance downward for a purpose to appear. The blank is then laid on the garment, its upper part 105 3 Shirred or gathered as at 23, and its upper edge where it is nearly straight from 6 to 6, and also where it is curved on each side from 6 to 7 is sewed along the line 20 to the back of the garment. The outer edge 110

from 7 to 8 is then sewed to the seam line S along the rear of the leg, and this stitching is continued from 8 to 9 along the extension 15; while the seam line S is closed 5 from the point 9 downward. The entire side piece 1 is then bent upward on about the transverse line 19, and the edge from 9 to 10 and then from 10 to 11 is sewed into the seam line of the front breadth of the leg. Finally the outside edge of the pointed extremity 12 is sewed into the seam line up 10 to the crotch 21 in front, as seen in Fig. 1. This is repeated for the other side piece or part 2 of the blank, and if desired the two 15 extremities 12 may lap each other slightly as seen in Fig. 1, but the inside edges of the seat piece from the extremities 12 upward to the point 14 are not connected to each other.

20 The result of applying a seat piece of this shape to a garment of the kind suggested is that the finished article when hanging up will be practically flat in front as seen in Fig. 1 and quite full in the rear as seen in Fig. 2, and in Fig. 3 I have drawn 25 the legs aside to show how this fullness is distributed. It is obvious that when the garment is applied to the wearer, the fullness of the thighs and the figure at the rear will fill out the seat piece as the shirring 30 23 permits, and even a wearer who is quite large around this portion of the anatomy will not cause the seat piece to hang open or to draw open in the ordinary positions 35 and movements of the body. Even when the extremities 12 are not lapped in front as seen in Fig. 1, I find that no buttons or other fastening devices are required, and that the parts of this device hang normally 40 closed. The extensions 15 down the inside of the legs prevent the movements of the legs in walking from drawing the device open, yet there is no seam in the crotch, as 45 both side pieces are stitched into the inner leg seams S which already existed. The whole device is cut from one piece of material which by preference will be the same as that of the garment to which it is applied, and if this is knitted fabric as usual 50 the seat piece will have the same lateral expansion as the other parts of the garment.

The device may be cut in sizes, and on lines which make the extension 15 quite large for wearers having unusually large thighs, and the shirring at 23 may be made to adapt the 55 garment to the size and shape of the wearer.

What I claim is:

1. The herein described blank for a seat piece for bifurcated garments, the same comprising a rounded end portion connected to 60 bifurcated right and left parts having, below the end of the bifurcation and approximately midway the length of the blank, lateral triangular extensions.

2. The combination with a bifurcated garment whose legs have inside seam lines; of a seat piece having a transverse upper part and right and left side parts depending therefrom and integral therewith, the top of the transverse part being shirred and 70 stitched to the back of the garment above the crotch, each side part having a substantially triangular extension on its outer edge between its upper and lower ends and folded on a transverse line through the tip of said 75 extension, and seams uniting the outer edge of the transverse part and each side part down to said tip with the rear seam line of the leg, and uniting the outer edge of said side piece from the tip to its lower 80 extremity with the front seam line of the leg up to the crotch.

3. The combination with a union garment whose legs have inside seam lines and whose back is cut transversely below the waist line; 85 of a seat piece comprising an upper part substantially straight across the center of its top and then curved down each side, and two side pieces depending from and integral with said upper part and each having 90 a triangular extension on its outer edge at about its mid-length, the center of said upper part being shirred, a line of stitching uniting the shirred edge with the back of the garment where it is transversely cut, and 95 other lines of stitching uniting the remainder of said upper part and the outer edge of each side piece with the rear seam line of each leg down to the tip of said extension and thence upward with the front seam line 100 of such leg.

LILLIAN F. DOTY.
